2,176,985

GRINDING MACHINE

Merton H. Arms, Springfield, Vt., assignor to
 Bryant Chucking Grinder Company, Springfield, Vt., a corporation of Vermont

Application October 27, 1933, Serial No. 695,455

35 Claims. (Cl. 51—50)

This invention relates to grinding machines or the like and has for its object to improve the actuation of such machines so that they may be under easy control of the operator. Thus he may at any time cause such operation of the machine as he may desire, such as producing the grinding operation, removing the wheel from cooperative relation to the work in such a manner that the work may be removed or replaced, or readily 5 inspected, or effecting dressing of the wheel. He may also control the speed of the machine in accordance with the requirements for working, truing the wheel, or idling.

A further object is to provide for such control 10 through the use of a single control handle. This control handle may be manipulated in one manner to control the direction of the wheel traverse and in another manner to provide for automatic production of other actions as will later more 15 fully appear. During grinding, the control may be automatic or manual as desired.

This handle, in accordance with an embodiment of the invention hereinafter more fully described, is mounted for rocking motion and for 20 linear motion perpendicular to the rocking plane, this last-mentioned motion being employed to control the traverse between the wheel and the work and the angular motion to control speed, wheel dressing, and wheel control for work inspection or replacement.

A further object is to provide for a dwell at one or both ends of the working traverse, but which will be ineffective whenever the grinding wheel is not in operative relation to the work.

Still another object is to so mount the traversing carriage that its traversing motion may be regular even at slow traversing speeds.

Further objects and advantageous constructions will be apparent from a more complete description of embodiments of this invention shown in the accompanying drawings, in which Figure 1 is a perspective of a grinding machine 40 embodying this invention.

Figure 2 is a fragmentary longitudinal section through the tool carrier slide bar and cylinders.

Figure 3 is a vertical section through the machine inwardly of the valve casing and showing the wheel slides in elevation and in raised position.

Figure 3a is a detail section on line 3a—3a of Figure 3.

Figure 4 is a fragmentary rear elevation of the rear end portion of the machine, parts being

broken away and in section and showing the slide retracted.

Figure 5 is a fragmentary end elevation showing the controlling valve casing, parts being broken away to show the pilot valve control 5 plate.

Figures 6 and 7 are details of control plates which may be used for the pilot valve.

Figure 8 is a detail section on line 8—8 of Figure 4.

Figure 9 is a fragmentary transverse section through the machine, but showing the opposite end of the wheel slide from Figure 3, the truing device being in wheel-truing position.

Figure 10 is a detail section showing a detent 15 mechanism for the rotary pilot and cylinder valves.

Figure 11 is a detail elevation showing the truing device in wheel-truing position.

Figure 12 is a diagrammatic view of the hydraulic system, the valves being in position to cause the wheel slide to move to the left in Figure 1 at grinding speed.

Figure 13 is a diagrammatic view of a portion of the hydraulic mechanism showing the parts 25 in wheel-lifting position and the wheel partly elevated.

Figure 14 is a sectional detail to a larger scale of the piston for the lifter valve shown in Figure 13.

Figure 15 is a view similar to Figure 12, but with the parts arranged to cause grinding traverse in the opposite direction or to the right.

Figure 16 is a front elevation to a larger scale than Figure 1 of the valve head and controlling 35 plates in position to cause carriage traverse to the right.

Figure 17 is a detail section to a larger scale on line 17—17 of Figure 16.

Figure 18 is a detail section on line 18—18 of 40 Figure 17.

Figure 19 is a detail section on line 19—19 of Figure 16.

Figures 20 and 21 are detail sections on the correspondingly numbered section lines of Figure 19.

Figure 22 is a detail section on line 22—22 of Figure 20.

Figures 23 and 24 are detail perspectives of co-operating parts of the dressing throttle shown in 50 Figures 19 to 22.

Figure 25 is a diagrammatic view of the hydraulic feed mechanism.

Figure 26 is a diagrammatic view illustrating 55

the several angular positions of the control handle.

Figures 27 and 28 are longitudinal sections to a larger scale through the pilot valve and related parts arranged for grinding stroke to the left and right, respectively.

Figures 29 and 30 are detail sections through the selector valve in left and right hand positions.

Figures 31 to 34, inclusive, are views similar to Figure 27, but showing the pilot valve in the angular positions for grind, dress, stop and fast, respectively.

Figures 35 to 37 are diagrammatic views somewhat similar to Figure 29, but showing the selector valve in dress, stop and fast positions, respectively.

Figures 38 to 41, inclusive, are views showing the reversing valve in different axial positions.

Figure 42 is a view similar to a portion of Figure 38 but showing a modification.

Figures 43a to 43g are detail cross sections on Figure 31 on the correspondingly lettered section lines.

Figures 44a to 44g are detail sections on the correspondingly lettered section lines of Figure 32.

Figures 45a to 45g are detail sections on the correspondingly lettered section lines of Figure 33.

Figures 46a to 46g are detail sections on the correspondingly lettered section lines of Figure 34.

Figures 47i to 47p are detail cross sections on the correspondingly lettered section lines of Figure 29.

Figures 48i to 48p are detail cross sections on the correspondingly lettered section lines of Figure 35.

Figures 49i to 49p are detail cross sections on the correspondingly lettered section lines of Figure 36.

Figures 50i to 50p are detail cross sections on the correspondingly lettered section lines of Figure 37.

Figure 51 is a view similar to Figure 12, but showing a modification.

Figure 52 is a view similar to Figure 16, but showing the same modification as Figure 51.

Figure 53 is a detail section on line 53—53 of Figure 52.

Figure 54 is a detail section on line 54—54 of Figure 53.

Figure 55 is a detail section on line 55—55 of Figures 53 and 54.

Figures 56 and 57 are views similar to Figure 53, but showing a dwell valve in different axial positions.

Referring first to Figure 1, at 1 is indicated a machine base which may house portions of

the hydraulic mechanism, as will later appear, and which also carries a work support indicated generally at 2, which in the present machine is intended to rotatably support work to be ground, more particularly, in the machine shown, internal

work which it is desired to grind on its inner face, and which work may be rotated in any suitable manner well understood in the art, during the grinding operation. At 3 is shown the grinding wheel which is carried by a suitable shaft

4 and which may be rotated as by means of a motor 5. This motor 5, as shown best in Figure 3, is connected in driving relation to the shaft 4 as by means of a driving belt 6 passed about a pulley 7 on the motor shaft, a pulley 8 on the

shaft 4 and about a pair of idlers 9 and 10.

Both motor 5 and grinding wheel shaft 4 are supported by an arm 12 connected to rock about the axis of a supporting bar 13. This supporting bar, as best shown in Figure 2, is mounted for reciprocation at opposite ends in fixed supporting bearings 14 and 15 and is reciprocated therein by oppositely disposed piston rods 16 and 17, having suitable pistons such as 18, at opposite ends which engage in hydraulic cylinders 19 and 20. A fluid such as oil for moving the bar 13 axially, which effects the traversing motions between the wheel 3 and the work holder 2, is supplied or discharged from the respective cylinders as by the pipes 21 and 22 (see Figures 12 and 15) by mechanism which will later be described. This general construction by which traverse is effected is similar to that shown and claimed in the Bryant Patent No. 1,920,290, granted August 1, 1933, for Grinding machines or the like.

In order to prevent irregular traversing motions of the bar 13 and the parts carried thereby, particularly at slow speeds, due to alternate sticking and pumping forward, means may be provided for floatingly supporting the bar on a lubricant under pressure to thereby aid in supporting the weight of the bar and parts carried thereby. As shown in Figure 2, the bar 13 may be supported in the bearings 14 and 15 on arcuate bushings 1300, having oil grooves as 1301 therein, to which oil under pressure is supplied from any suitable source through pipes 372. This oil may be supplied by the hydraulic system which will be later described. Abutment shoes 1303 adjustable vertically as by screws 1304 hold the bar 13 seated on the bushings 1300. An oil seal ring at 1305 of any suitable description may be employed at one or both ends of the bearings and oil leaking by may be removed as through drain pipes at 1306.

As shown best in Figure 3, the lower end of the arm 12 is provided with a bracket portion 25 having a cam follower 26. In normal grinding operation this follower 26 in the form of a bar engages and traverses a roll 27 on a feed shaft 28, the parts being so related that when in such engagement the grinding wheel is in proper axial position to cooperate with work carried by the holder 2. In Figure 3 the grinding wheel is shown as moved laterally out of this operative position for inspection, removal, or replacement of the work, this being effected in a manner which will later be described. Axial motion of the feed shaft 28 by rotation of the nut 29 imparts the lateral motion of the wheel for feeding relative to the work and the means by which this is accomplished will also later be described.

Control of the various operations including working traverse between the wheel and the work, a rapid traverse for idle motion, and extended traverse for wheel dressing and the retraction of the wheel out of line with its working traverse into the position shown in Figure 3, are all produced through suitable motions imparted to a common control member, which comprises the handle 30, through a hydraulic system which will now be described.

Referring first to Figure 15, at 35 is indicated an oil pump housed within the base 1, by which the oil is taken from a supply tank 36 and delivered through the pipe 37 to a main valve casing 39 containing the various control valves which will later be described. A relief valve set to maintain a predetermined constant supply pressure is shown at 38 for discharging excess oil 76

from the supply line 37 into the tank. The oil is returned from the main valve casing through the discharge line 31 and a back pressure valve 40, which insures sufficient pressure in the system at all times, say, about ten pounds, to prevent the entry of air. Oil with a pressure of, say, 100 to 120 pounds is conducted through the supply line 37 to the main valve casing. Oil may be taken from the pipe 37 through the small pipe 370 and the filter 371 to the branch pipes 372 leading to the slide bearing bushings 1300 hereinbefore mentioned. A relief valve 374 may be used to determine the pressure in the pipes 372 and a pressure gage may be positioned at 375.

Three main control valves are employed, a pilot valve 41, a reversing valve 42 and a selector valve 43. The control handle 38 is fixed directly to the pilot valve 41. This pilot valve 41 has an axial movement substantially parallel to the wheel traverse direction and a rocking movement, the reversing valve 42 has an axial movement only, and the selector valve 43 has both axial and rocking motions. The angular motions of the selector valve are shown as produced through angular motions of the pilot valve. This is indicated diagrammatically on Figures 12 and 15 and shown in detail in Figure 9. The pilot valve 41 carries a gear 45 which meshes in sliding engagement with a partial gear 46 on a stub shaft 47, this in turn meshing with a gear 48 on the selector valve with which it also has sliding engagement. In order to retain these two valves in any desired of their several angular positions, the partial gear 46 may, as shown best in Figure 10, be provided with four peripheral depressions or notches 50 within which may engage a ball 51 backed up by a spring pressed plug 52. Each of these four angular positions of the control handle 38 corresponds to certain controls in the order of sequence from the upper position of the handle, as shown best in Figure 26 to its lowest positions as follows: grind, dress, stop, and fast. In the upper position of the control handle, axial position of this determines the direction of traverse 45 between the wheel and the work at grinding speed within the limits of axial motion suitable therefor. In the other angular positions, other controls are effected as will later more fully appear.

Grinding position.—The grinding positions of the various valves are shown in Figures 12 and 15, in Figure 12 the parts being in position to effect traverse toward the left and in Figure 15 to effect traverse toward the right. Referring first, then, to Figure 12, oil under pressure passes from the pipe 37 to the correspondingly numbered passages, around the selector valve 43, around the reversing valve 42, and to the pilot valve. The pressure line 37 is connected in this position of the valve (Figures 12, 27 and 31) through the valve passage 410 to the pilot line 64, and the valve likewise connects the pilot line 63 through the valve passage 411 and connection 62 to the discharge line 31. When the pilot valve is moved to the extreme right hand position, as shown in Figure 15, the pilot line connections are reversed, so that the line 64 is open to the discharge and the line 63 is open to the pressure line 37. Auxiliary lines 60 and 61 are at times under the same pressure conditions as the lines 64 and 63, respectively, these auxiliary lines being employed for the purpose of effecting a quick reversal as will later appear, but these lines are closed by the pilot valve in grind position. The pilot line 64 extends nearly to the right hand end of the re-

versing valve 42 and the pilot line 63 extends nearly to the left hand end of the same valve, and when pressure is applied to either of these lines the reversing valve is moved from one extreme endwise position toward the other of its extreme axial positions. It will be noted that the first part of the motion of the reversing valve 42 to the left, cuts off the passage 63 by the head of this valve which passage later on in this stroke is again opened, while the first motion of the reversing valve in the other direction similarly cuts off the passage 64 which is later again re-opened. When the reversing valve is at its extreme left hand position, as shown in Figure 12, it opens communication from the pressure line 37 through valve passage 420 to the line 22 which leads to the right hand end of the power traversing cylinder so that this cylinder and the wheel slide move to the left, while the line 21 leading from the left hand end of the cylinder passes to a lifter valve, the function of which will be later described, at 65, past this valve, and back to the main control casing through the pipe 66 and is connected by passage 421 in the reversing valve to the return lines 67 and 68, which are joined together beyond the needle valve 69 and pass to a grinding throttle valve at 70. The setting of valve 70 determines the speed of grinding traverse. This throttle valve is shown in Figures 17 and 18 and will be more fully described later. In the grinding position of the pilot and selector valves, the oil passing the valve 70 discharges through the passage 71 around the selector valve and through the valve passages 430 and 431 and out to the discharge passage 31, which leads back to the tank. When the wheel slide nears the right end of its stroke, the pilot valve is moved to the right by impingement of the cam 81 on the plate 100. The first part of this motion acts to close off the passage 67 by the pilot valve, so that all the discharge of oil must take place through the needle valve 69 which so restricts the flow that the motion of the wheel slide is arrested to an extent determined by the adjustment of this needle valve 69 before connections producing its stop and return traverse are effected.

Similarly with the reversing valve at its extreme right hand position, as shown in Figure 15, the pressure line 37 is open to the pipe 66, past the valve 65, to the pipe 21 leading to the left hand cylinder, while the right hand cylinder is connected through the pipe 22 and past the reversing valve to the return passage 72, to the return line 67, and also through the auxiliary return line 73, past the needle valve 74, to the same return line 67 which leads to the valve 70 through the passage 71 and past the selector valve through passages 430 and 431 to the discharge line 31. Near the end of the wheel slide stroke in this direction, the discharge is cut off by the pilot valve and is compelled to pass through the needle valve 74. This acts in the same manner as the valve 69 to arrest the motion of the wheel slide before it is reversed at the right hand end of its stroke. This checking of the rate of speed of the wheel slide near the ends of its stroke while permitting it to travel at its reduced and adjustable speed to the extreme end of the stroke causes the speed of travel at the intermediate portion of the stroke to have no effect on the amount of over-travel. Otherwise this intermediate speed would have considerable influence due to the cushioning effect of air in the oil, elasticity of the pipes and other factors, on the extent of over-travel, such over-travel being greater the 75

higher the intermediate speed. By checking the slide speed just before the end of the stroke to a low value, the slide may be brought to a definite limit uniformly whether the intermediate rate of travel is fast or slow. This is of special importance when grinding to a shoulder. Thus the power traverse of the wheel will be made in opposite directions, depending on the position of the reversing valve, the position of which in turn is controlled by the axial position of the pilot valve and the control handle 30.

Automatic means may be provided for reversing the direction of traverse. As shown in Figures 12, 15, and 16 this means comprises a pair of cam dogs 80 and 81 adjustably supported angularly on a cam drum 83 whereby the limits of traversing motion may be adjusted in accordance with the work being operated upon. This cam drum 83 is fixed to a rock shaft 84 (see particularly Figures 5 and 8), journaled crosswise of the power cylinders for effecting the traverse, and having fixed at its end opposite to the cam drum 83 a gear 86 which meshes with a rack bar 87. This rack bar is mounted for reciprocation within a frame portion 88, its outer end being enclosed by a protective housing 89. Adjacent to the inner end of this rack bar 87, as shown best in Figure 3a, it is provided with a notch 90 within which rides a peripheral portion 91 of an arcuate member 92 (see Figure 3) which is attached to the wheel arm 12 as by means of bolts 93 passing through slots 94 in the member 92. This arcuate member 92 is arranged concentric with the bar 13 so that its peripheral portion 91 engages in the slot 90 throughout the range of angular motion of the arm 12 so that the position of this arm axially of the bar 13 continuously controls the axial position of the rack bar 87, and thus the angular position of the cam drum 83. For cooperation with the cams 80 and 81 of this drum, the pilot valve 41 is shown as provided with a control plate 100. Two types of such control plate are shown in elevation in Figures 6 and 7. In Figure 6 the control plate is shown as provided with an arcuate portion 101 of relatively large diameter and an arcuate portion 102 of a smaller diameter. It will be noted that the cam 80 is of less height than the cam 81. The cam 81 is of sufficient height so that no matter in which of its four angular positions the pilot valve is placed, this cam 81 will impinge upon its left hand face when the traverse of the grinding wheel is taking place to its extreme left hand position and move the pilot valve to reverse the traverse direction so that the wheel slide is moved to the right. In the grinding angular position of the control plate, however, the portion 101 of the plate is in operative position relative to the cam 80 so that when this cam impinges on this portion 101 at the opposite end of the grinding traverse, the pilot valve is moved in the opposite direction to reverse the direction of traverse so that the wheel will move to the left. When, however, the handle 30 is in any of its other angular positions, as dress, stop, and fast, the portion 102 of this control plate is in line with the cam 80, but this cam is too short to impinge on this portion 102, so the traverse is not reversed at the normal right hand end of the grinding stroke, but is extended. During such extended portion of the stroke the dressing of the wheel is accomplished and the retraction of the wheel out of working alignment with the work is also effected as will later more fully appear.

75 In Figure 7 a modified form of control plate is

shown in which the portion 101 is as before, but the smaller diameter portion 102a is cut away still further adjacent to the portion 101 by the notch 103 sufficiently so that the cam 81 is also permitted to go by without contacting with the cam plate, this being shown as in the dress position. This will permit a manual control of the extent of traverse to the left which may be found at times useful in grinding up to a shoulder, or in any other situation where a manual control of the inner limit of grinding may be found desirable. Since the dressing of the wheel is done in the extended traverse position, this is not brought into action during this manual control of the left hand traverse limit. As a safety measure to prevent too far outward motion of the grinding wheel, a hydraulic bumper 110 may be employed, this bumper being shown as mounted on a stop bar 111 carried by a portion of the machine frame. Oil is supplied back of the bumper 110 from the pilot line 63 through the pipe 112 (see Figure 13). When the wheel slide strikes this bumper 110 the oil confined in the bumper cylinder is forced out through a throttle 113 as shown in Figure 13. The stop rod 114 has a head 115 at its inner end which engages back of the arcuate plate 92 when the arm 12 is in its retracted position (shown in Figure 3) in order to hold it from accidental axial motion when the grinding wheel is in its inoperative and retracted position. At 116 (see Figure 1) is shown a bumper to limit the inward motion of the grinding wheel.

Wheel dwell.—During the grinding stroke, especially when grinding to a shoulder, it is desirable to have the wheel dwell or hesitate before reversing at one or both ends of the hole, this dwell being of sufficient length to insure the grinding action of the wheel on the entire periphery of the work. This is accomplished in the construction shown in Figure 12 and 15 and in enlarged views in Figures 38 to 41, by the heads of the reversing valve cutting off the passages 63 and 64 as heretofore described. The oil may pass into the chambers beyond the ends of this reversing valve through the passages 63 and 64, past the ball check valves 120 and 121 freely, but these check valves close on discharge of oil so that it is compelled to pass the throttles 122 or 123 during the time that the valve heads cover ports 60 leading to passages 63 and 64, respectively. The necks 124 or 125 of the reversing valve finally re-open the passages 63 or 64, respectively, permitting the reversing valve to move quickly to its extreme position. The quick start and finish of the reversing valve motions permits the cylinder lines to be quickly opened and closed, while the slow intermediate speed gives an interval regulated by the throttle 122 or 123 during which oil is trapped in the wheel slide cylinders and the slide remains at rest. When the control lever 30 is in any other angular position than grind, the passages 60 and 61 in communication with the end chambers 126 and 127, respectively, are uncovered, so that the reversing valve may move without restriction and there will be no dwell.

These motions of the reversing valve are shown in Figures 38 to 41, inclusive. In Figure 42 is shown a slight modification in which the reversing valve is not provided with the necks 124 and 125, in which case there is a slow final motion of the reversing valve and the wheel slide does not immediately resume its full speed grind motion after a limited dwell period.

Dressing position.—The effect of turning the 76

5 pilot valve to the dressing position is to render the stop 88 ineffective to limit the extent of traversing motion to the right as heretofore explained. The position of this valve for effecting 10 traverse to the left is as shown in Figure 32 and the sectional details (Figures 44a to 44g). The 15 port connections are the same as for the grinding position with the exception that passages 60 and 61 to the ends of the reversing valve are 20 unrestricted, the passage 61 being directly open 25 to the passage 62 past the pilot valve flat 413 in the left hand position of the valve and directly 30 opening to the passage 37 past the flat 410 at the right hand position of the valve, and the 35 passage 60 being directly open to the passage 37 past the valve flat 410 at the left hand position of the valve and directly open to the passage 64 past the valve flat 412 at the right hand position 40 of the valve. Thus there is no restricted opening to the reversing valve which can therefore 45 reverse quickly so that no dwell is produced.

The selector valve when first turned to dressing angular position permits rapid discharge just as in the grinding position. When the wheel 50 has been moved beyond its grinding position, right hand stop 88 being then ineffective to reverse the pilot valve, a cam element 135 on the cam drum 83 engages a roll 136 on a lever 137 and swings this lever so that its lower end having 55 a follower 138 engaging a peripheral recess 139 in the selector valve forces this selector valve to the right from the position of Figure 30 against the action of a spring plunger 149 into the position shown in Figure 35. This cuts off the two passages 430 and 431 so that the oil 60 must be discharged through the shorter passages 432 and 433 and the amount flowing will then be determined by the setting of the dressing throttle 131 controlling the flow of oil in the 65 passage 130. Oil will then be admitted from the pressure line 37 into the dressing tool operating line 140 through the valve passages 434 and 435 (Figures 48i and 48j). This line 140 leads past a shut off valve 140a to a power cylinder 141, the 70 piston 142 of which is connected at its rear end through the link 143 to a diamond holder 144 which is rockably supported on a bracket 145 at the back of the machine, thus to depress this diamond into the full line position shown in Figure 9 where it is positioned to be traversed by the wheel which is now retracted from the work, this traverse of the wheel relative to the diamond being under the full control of the operator. When the operator moves the handle 75 axially to return the wheel toward the work, the selector valve is again permitted to resume its left hand position of Figure 30 as soon as the pressure on the cam roller 136 has been relieved, whereupon the selector valve connects the line 80 140 directly to the discharge 31 past the valve neck 436 so that the diamond may return to its inoperative or dotted line position shown in Figure 9. With the control lever 30 in any other position than dress, the selector valve will be in 85 such angular relation that no matter what its axial position no connection will be made from the pressure line 37 to the line 140. A suitable spring 146 in the diamond holder cylinder 141 holds the diamond retracted even under the back 90 pressure of the hydraulic system by reason of the back pressure valve 40.

Stop position.—In the stop position of the control handle 30 the selector valve blanks all of the three possible discharge ports 11, 130, and a third discharge port 150, so that no matter what the

positions of the other valves may be the wheel slide cannot be moved by the hydraulic system, but in this stop position this valve opens ports 437 and 438 past the valve neck 436 to connect the lines 66 and 21 through the passages 151 and 152, as shown best in Figures 36 and 49o, which will permit oil to pass from one to the other of the cylinders so that the slide may be moved by hand or any other means aside from the hydraulic actuating system.

Fast motion position.—In the fast motion position of the pilot valve the connections are the same as for dressing and stop, the tool slide being permitted its extended traverse to the right. Details of this valve and the various port connections are shown in Figure 34 and Figures 46a to 46g with the valve in position to cause the traverse to the right. The selector valve is then positioned to discharge freely from either power cylinder through the passage 150 and the valve 20 passages 430, 431 to discharge 31 (see Figures 37, 50k and 50n). The axial motion of the selector valve to the right by impingement of the cam 135 on the lever 137 has no effect to change the speed of wheel slide motion when the selector 25 valve is in fast motion angular position, the valve passages 430 and 431 maintaining connection with the discharge line 31 in both axial positions of this selector valve.

Wheel arm lifter.—When motion to the right 30 has proceeded to a point beyond the dressing position with the pilot valve in either dress or fast angular positions, the slide-retracting mechanism is caused to operate to lift the arm 12 so as to swing the wheel out of its normal traversing line and there hold it. This mechanism is shown in detail in Figures 13, 14 and 15. Attached to the wheel slide or arm 12 is a stud 160 on which is mounted a roll 162 which in its extreme right hand position engages upon the 35 upper end of a ram 163. At this extreme end of the stroke the end of the stud 160 strikes a shoe 164 carried by the upper end of a latch 165 fulcrumed at 166 to a fixed frame member and normally held with its lower end engaged under a 40 head 167 of the valve 65, to which mention has heretofore been made, as by a spring 169. By this latch this valve 65 is normally held in its upper position shown in Figure 15. When the pilot valve is in its right hand position pressure 45 is applied to the shoulder 170 from the pilot line 63, while the oil in the chamber 171 below the valve and in a second chamber 172 below a piston 173 is free to exhaust through the pilot line 64, the piston 173 having a passage 174 therethrough 50 which may be closed by a ball check valve 175. The pilot valve being in its right hand position when the slide moves to the right end of its stroke, the valve 65 and the piston 173 will drop 55 as soon as the latch is released by the stud 160 striking on the shoe 164. Oil flowing from the line 66 into the line 21 is cut off by the dropping of this valve 65, as shown in Figure 13, and diverted into a passage 180 around the valve 65 to the passage 181 around the valve 182 past the ball check 183 to the line 184 and into the lifter cylinder 185 beneath the plunger 163. When the lifter plunger 163 is in its lowest 60 position the valve 182 is depressed by a pin 186 attached to an extension 187 of the lifter ram 70 163, as is shown in Figures 13 and 15, in which latter figure for convenience the valve 182 is shown in two parts at different elevations. This valve 182 moves upwardly with the ram due to the action of a spring 190 beneath it until a shoul- 75

der 181 at its lower end prevents further motion. The passage 181 is then connected directly to the passage 184 so that oil flowing to or from the cylinder 185 is not required to pass through the check valve 183 or the throttle valve 182. By this means the plunger is raised quickly to its upper limit of motion, thus holding the grinding wheel retracted so that work may be inspected or removed or replaced as desired. It will be noted that this is done automatically by the operator moving the control handle to the right in fast motion angular position. In order to return the grinding wheel to its line of traverse it is only necessary to move the control handle 30 to the left in any of its angular positions. In doing this, pressure is applied to the right slide cylinder through the line 22, but the slide cannot move to the left while the lifter cylinder line 21 is closed by the valve 65. Pressure is also applied through the pilot line 60 to the under side of the piston 173 which is thereby lifted to the position shown in Figure 14. The valve 182 which is in its upper position at this time cuts off access of oil to the passage 185. The valve 65 is thus raised only that amount caused by the raising of the piston 173, the valve 65 then resting thereon and in this position the valve 65 connects the passage 181 with a line 196 leading directly to the discharge line 31, past a check valve 197. This permits the plunger to drop quickly until as it approaches the lower end of its stroke, the valve 182 is depressed by contact with the pin 186, cutting off the line 184 directly to the discharge line 31 and checking the descent of the plunger by requiring the oil remaining in the cylinder 185 to escape around the throttle 192. When the valve 182 is fully depressed by the pin 186 oil is permitted to flow from the pilot line 64 through the passage 198 around the valve 182 through the passage 195 and through passages 199 in the piston 173 to the lower face of the lifter valve 65. This causes this valve 65 to be raised and latched, thus connecting the line 66 with the line 21 and so permitting the slide traverse to be resumed. A small bleeder line 200 is connected from the lifter cylinder 185 to the supply tank to prevent pressure being built up under the piston as the result of leakage. Similar lines may be placed where needed to conduct leakage past valves or other parts back to the tank.

Feed mechanism.—Means are provided by which the feed mechanism is actuated at each end of the wheel traverse, mechanism for accomplishing this being illustrated in Figure 25. The left and right power cylinder pilot lines 63 and 64 lead to the upper and lower end portions of a pressure cylinder 210 within which rides a piston 211. Between its ends this piston is provided with cam recesses 212 and 213, forming between them a cam hump 214. This cylinder 210 is provided with a slot 215 through one side through which may project a cam follower roll 216 at the end of an arm 217 clamped to a shaft 218. This arm 217 is normally pressed against the piston 211 as far as permitted by an adjustable stop screw 226 by a spring 219, the parts being so arranged that on reciprocation of the piston 211 toward either end of its cylinder 210, the hump 214 causes the arm 217 to be rocked against the tension of the spring 219 which then returns to initial position. The shaft 218 carries an arm 220 to which is pivotally secured a latch 221 which has a finger portion 222 engageable with the teeth of the feed wheel 223 by rotation of which the nut 29 is rotated. A lifting dog 224

adjustably secured angularly about the axis of the feed shaft 225 and turning therewith serves to lift the latch to stop the feed after a predetermined extent, while adjustment of the stop screw 226 determines the extent of feed of each actuation of the plunger 211. Thus when the pilot line 63 is open to pressure and the pilot line 64 is open to discharge at one limit of traverse motion, the piston 211 is driven in one direction to produce a feed of the wheel, and at the other end of the wheel traverse when the pilot line 64 is open to the pressure line and the pilot line 63 is open to discharge, the piston 211 is given a stroke in the opposite direction thus to produce another feed actuation of the grinding wheel.

Main throttle.—This main throttle 70 to which reference has heretofore been made is shown in detail in Figures 17 and 18. It has a segmental plate 250 eccentrically journaled on a shaft 251, this plate riding over a flat valve seat 252 into which the passages 150 and 71 open. The passage 150 has its outer edge wholly within the periphery of the segment, while the passage 71 so opens through the flat seat 252 that when the end portion 253 of the valve plate is thereover, it is entirely covered, but as this valve plate is swung clockwise, as viewed in Figure 18, it is gradually uncovered at its outer edge. Motion in this direction serves to uncover the passage 150 completely with a small angular displacement of the plate 250 and thereafter the opening 71 is gradually opened. As before noted, the passage 150 is for fast motion so that when the shaft 251 is turned to fully open this passage the flow of oil is unrestricted, whereas when the parts are in grind position the flow is through the passage 71, so that the rate of flow is more or less restricted, depending on the particular angular setting of this valve plate 250. By completely closing this valve at any time, as shown in Figure 18, traverse motion may be completely stopped. The passage 67 leads directly to the upper face of this plate 250. Spring pressed plugs 255 bearing against a disk 256 secured to the outer end of the shaft 251 as by a screw 257, and seated in sockets in a hub portion 260 which is provided with an actuating handle 261 and which is keyed to the shaft 251 as by the key pin 262, hold the hub portion in frictional engagement with the valve cap member 270 so that the handle 261 remains in any angular position in which it may be set. The hub 260 may be provided with stop shoulders 263 and 264 for cooperation with a stop pin 265, thus to limit the extent of angular motion of the plate 250. The cap member 270 may be secured in position against the main portion of the valve case as by bolts 271.

Dressing throttle.—The speed of traverse for dressing may be regulated separately from the regulation of the grinding speed, this being accomplished by means of the dressing throttle 131, heretofore mentioned, this being shown in Figures 19 to 24. The cap member 270 heretofore mentioned has a chamber 276 opposite to the end of the passage 130 leading to the selector valve. In this chamber is positioned a valve plate 276 mounted eccentrically to a shaft 277 by which it may be turned. The shaft 277, as shown best in Figure 22, is provided with a socket 278 in which is slidable a pin 279 backed up by a spring 280. This pin 279 is thus pressed into a socket portion 281 of the plate 276 and acts to hold this plate firmly seated against the end face of the main valve casing opposite to the passage 130 and provides an axis of rotation for the plate. The 75

shaft 277 is also provided with a head 282 having a transverse rib 283 on either side of the socket 278, one of these ribs having an extended portion 284. These ribs and the extended portion engage in a slot 285 in the outer end wall of the valve plate 276, the extended portion 284 engaging in a deep end portion 286 of this slot, whereby rotary motion imparted to the shaft 277 likewise imparts an eccentric rotation to the valve plate 276 so as to more or less cover the end of the passage 130, depending on the angular position of this shaft. The head 282 of this shaft bears against a washer 288 at the base of the socket 275 and its outer end has secured thereto an actuating knob 290. This knob is provided with a segmental cut away portion 291 on its inner face which cooperates with a stop pin 292 to limit the angular rotation of this shaft.

Motor controls.—Means may be provided by which the pump motor may be started only on stop position of the control handle and whereby the rotation of the work may be stopped when the wheel is retracted and the slide lifted and may be started when the traverse is to be resumed. To this end a pump motor limit switch 300 and a work-rotating motor limit switch 301 are shown as provided with push buttons 302 and 303, respectively, cooperating with a cam end portion 304 on the selector valve. In the stop position the push button 302 may be sprung out by depressing the usual starter button of such limit switches and in the fast position the button 303 is in position to permit the stopping or starting of the work-rotating motor.

Modified mechanism having separate dwell valve.—In Figures 51 to 57, inclusive, a mechanism is shown in which the dwell at opposite ends of the grinding stroke is effected by an independent dwell valve separate from the pilot and reversing valves. The selector valve in this construction is the same as that in the construction previously described and has the same angular positions and it is therefore given the same number 43 as in the construction previously described. The pilot and reversing valves, however, are of somewhat simpler construction and are indicated by separate reference numerals 500 and 501. The pilot valve 500 has attached thereto the operating handle 30 and the control plate 100, but instead of the flats intermediate its ends it is provided with a pair of necks 503 and 504. The ports controlled by the pilot valve are the same in each of its four angular positions, the controls being separate only in so far as the angular positions of the control plate 100 are concerned. The oil under pressure is delivered through the passage 37 around the selector valve 43, past the reversing valve 501, and around the pilot valve 500. In the extreme left hand position of the pilot valve shown in Figure 51 connections are made from the pressure passage 37, past the neck 504 to the pilot passage 64, which leads to the right hand end of the reversing valve 501, so that this valve is moved to its extreme left as shown in this view. At the same time the pilot passage 63 is open to the discharge line 31 through the passage 505. On the reverse position of the pilot valve the pilot line 63 is connected to the pressure line 37, and the pilot line 64 is connected through the passage 505 to discharge. The pilot line 63 leads to the left hand end of the reversing valve 501 and the pilot line 64 leads to the right hand end of this valve. This reversing valve has two neck portions 510 and 511. In the left hand position of the revers-

ing valve shown in this figure, the pressure line 31 is placed in communication with the right hand power cylinder through the line 22 while the line 66, which passes by the lifter valve and to the left hand power cylinder through the passage 21, is open to the passage 512, which leads to the main throttle 10. In the right hand position of the reversing valve, these connections are reversed so that the pressure line 31 is placed in communication with the line 66 leading through the line 21 to the left hand power cylinder, and the line 22 leading to the right hand cylinder is placed in communication with the line 512 leading to the main throttle 10. The outlet from the main throttle 10 which leads to the selector valve through the grind passage 11, instead of passing directly thereto, as shown in Figures 12 and 15, leads from the selector valve through the passage 515 to a port 516 controlled by the dwell valve indicated at 520 and which is mounted for reciprocation in a casing 521 which may be secured by any suitable means to the main valve casing. This dwell valve 520 is provided with a pair of spaced necks 522 and 523 and reduced end portions 524 and 525, respectively. Motion is imparted to the dwell valve by pressure derived through the pilot lines 63 and 64. The pilot line 63 communicates with the left hand end of the dwell valve through the passage 526, past the ball check 527 and the throttle needle valve 528. The passage 64 communicates with the right hand end of the dwell valve through the passage 530, the ball check valve 531, and the throttle needle valve 532. When the pilot line 63 is first opened to pressure from the pilot valve, oil under pressure passes freely past the check valve 527 and starts the dwell valve rapidly toward the right, but the first part of this motion closes off the port 516, thus preventing the discharge of oil past the main throttle so that the traverse cannot begin. This movement to the right also closes the free passage to the pilot valve from the line 64, so that the discharge on the opposite side through the pilot line 64 must take place past the throttle valve 532. As soon as the passage 530 is uncovered by the neck 523, the discharge through the pilot line 64 may again take place freely so that the dwell valve moves rapidly to its extreme right hand position shown in Figures 52 and 53, and opens the port 516, thus again permitting the discharge through this port through the passage 540 and into the passage 71. On reverse actuation of the dwell valve, similar action takes place to first cut off the discharge past the neck 522 of the dwell valve and then to open it again past the neck 523, free passage from the left hand end of the dwell valve being restricted for a time during this motion by closing off of the free opening to the passage 526. The ends of the bore containing the dwell valve may be closed off by the threaded plugs 541 and 542.

From the foregoing description of certain embodiments of this invention it should be evident to those skilled in the art that various other modifications may be made without departing from the spirit or scope of this invention as defined by the appended claims.

I claim:

1. A machine of the class described, comprising a work holder, a tool, a hydraulic mechanism for producing relative traverse between said tool and holder, said mechanism including a source of hydraulic pressure, a reversible hydraulic motor, a reversing valve, connections from said

- 5 valve to said motor for causing motion of said valve to control the flow of fluid to drive said motor in opposite directions, a pair of independently adjustable throttling devices, one for each direction of traverse, and means acting to first render the proper device effective on the discharge from said motor to slow the traverse to a predetermined rate, and effective on said reversing valve thereafter to shut off said motor and then to reverse said motor.
- 10 6. A machine of the class described, comprising a work holder, a tool, a hydraulic mechanism for producing relative traverse between said tool and holder, said mechanism including a source of hydraulic pressure, a reversible hydraulic motor, a reversing valve, connections from said valve to said motor for causing motion of said valve to control the flow of fluid to drive said motor in opposite directions, a pair of independently adjustable throttling devices, one for each direction of traverse, and means acting to first render the proper device effective on the discharge from said motor to slow the traverse to a predetermined rate, and effective on said reversing valve thereafter to shut off said motor and then after a dwell of predetermined time to reverse said motor.
- 15 7. A machine of the class described, comprising a work holder, a tool, a hydraulic mechanism for producing relative traverse between said tool and holder, said mechanism including a pilot valve, and a reversing valve, said reversing valve controlling the supply of fluid to produce such traverse and said pilot valve controlling by fluid pressure the position of said reversing valve and having means to reduce the speed of traverse adjacent to its limits before said reversing valve acts to reverse the direction of traverse.
- 20 8. A machine of the class described, comprising a work holder, a tool, a hydraulic mechanism for producing relative traverse between said tool and holder, said mechanism including a reversing valve for stopping and reversing the direction of traverse, an axially movable valve controlling by its axial position the position of said reversing valve, said mechanism including means controlled by said axially movable valve for checking the traverse motion just prior to stopping and reversing the direction thereof, and independent means for adjusting the extent of checking at opposite ends of said traverse.
- 25 9. A machine of the class described, comprising a work holder, a tool, a hydraulic mechanism for producing relative traverse between said tool and holder, a control member having a traversing and an angular motion, and valve means responsive to the traversing motion of said member to control the direction of traverse between said tool and work holder and to check the traverse adjacent to its ends before reversal thereof, and valve means responsive to the angular position of said member for controlling the speed of such relative traverse.
- 30 10. A machine of the class described, comprising a work holder, a tool, a hydraulic mechanism for producing relative traverse between said tool and holder, a control member having a traversing and an angular motion, and valve means responsive to the traversing motion of said member to control the direction of traverse between said tool and work holder and to check the traverse adjacent to its end before reversal thereof, and valve means responsive to the angular position of said member for controlling the speed of such relative traverse, said speed control valve having a stop position in which relative traverse in either direction independent of said hydraulic mechanism may be effected.
- 35 11. A machine of the class described, comprising a work holder, a grinding wheel, mechanism for producing relative traverse between said wheel and work holder, means for moving said wheel relative to said holder laterally of its direction of traverse to an inoperative position, a wheel truing device, means actuatable to move said truing device between wheel truing and inoperative positions, a member having angular and linear mo-
- 40 45 50 55 60 65 70 75 80 85 90 95 100 105 110 115 120 125 130 135 140 145 150 155 160 165 170 175 180 185 190 195 200 205 210 215 220 225 230 235 240 245 250 255 260 265 270 275 280 285 290 295 300 305 310 315 320 325 330 335 340 345 350 355 360 365 370 375 380 385 390 395 400 405 410 415 420 425 430 435 440 445 450 455 460 465 470 475 480 485 490 495 500 505 510 515 520 525 530 535 540 545 550 555 560 565 570 575 580 585 590 595 600 605 610 615 620 625 630 635 640 645 650 655 660 665 670 675 680 685 690 695 700 705 710 715 720 725 730 735 740 745 750 755 760 765 770 775 780 785 790 795 800 805 810 815 820 825 830 835 840 845 850 855 860 865 870 875 880 885 890 895 900 905 910 915 920 925 930 935 940 945 950 955 960 965

tions, means responsive to the linear positions of said member for controlling the direction of traverse and to check the traverse adjacent to its ends before reversal thereof, and means responsive to the angular position of said member to control at a predetermined point in said traverse the operation of said lateral moving means, and said wheel truing device.

12. In a machine of the class described, a work holder, a tool, means for effecting traverse between said holder and tool, manual and automatic means for controlling said traverse between definite limits, means for producing a dwell in said traverse at said limits, said control means including mechanism actuatable to render said automatic control only inoperative at one end of said traverse, thereby to permit an extended traverse under manual control, said mechanism including means to render said dwell means inoperative when said automatic control is rendered inoperative.

13. In a machine of the class described, a work holder, a tool, means for effecting traverse between said holder and tool, manual and automatic means for controlling said traverse between definite limits, means for producing a dwell in said traverse at said limits, said control means being actuatable to render said automatic control inoperative at one end of said traverse and permit an extended traverse under manual control during which said dwell means is inoperative, and means operable automatically at a predetermined point at said extended traverse to move said tool out of position out of the line of traverse.

33 14. In a machine of the class described, a work holder, a tool, means for effecting traverse between said holder and tool, manual and automatic means for controlling said traverse between definite limits, means for producing a dwell in said traverse at said limits, said control means being actuatable to render said automatic control inoperative at one end of said traverse and permit an extended traverse under manual control during which said dwell means is inoperative, and means operable automatically at a predetermined point at said extended traverse to move said tool out of position out of the line of traverse and to stop further traverse in said extended direction.

15. In a machine of the class described, a work holder, a tool, means for effecting traverse between said holder and tool, manual and automatic means for controlling said traverse between definite limits, means for producing a dwell in said traverse at said limits, said control means being actuatable to render said automatic control inoperative at one end of said traverse and permit an extended traverse under manual control during which said dwell means is inoperative, means operable automatically at a predetermined point at said extended traverse to move said tool out of position out of the line of traverse, and means for holding said tool against return toward said limited traverse while it is out of line therewith.

65 16. In a machine of the class described, a work holder, a tool, means for effecting traverse between said holder and tool, a member having a linear and a rocking motion for controlling said traversing means, a handle secured to said member and by which its position may be controlled, automatic means for actuating said member to reverse the traverse direction at desired traverse limits effective at one of said limits when said member is in one angular position only, and means effective when said member is in said one angular

position only to produce a dwell in said traverse at its limit, whereby on turning said member by said handle to a different angular position, said traverse may be extended beyond said one limit under manual control and while said dwell means is inoperative.

17. In a machine of the class described, a work holder, a tool, means for effecting traverse between said holder and tool, a member having a linear and a rocking motion for controlling said traversing means, a handle secured to said member and by which its position may be controlled, automatic means for actuating said member to reverse the traverse direction at desired traverse limits effective at one of said limits when said member is in one angular position only, means for producing a dwell in said traverse when said member is in said one angular position only, whereby on turning said member by said handle to a different angular position, said traverse may be extended beyond said one limit under manual control and without dwell, and means controlled by such angular position to determine the speed of such traverse.

18. A machine of the class described, comprising a work holder, a tool, hydraulic means for producing relative traverse between said holder and tool, control mechanism for said means comprising a pilot valve having traverse checking means, a reversing valve for controlling the direction of traverse, and a selector valve, and means for actuating said pilot valve to render said checking means operative and to then change the position of said reversing valve to reverse the direction of traverse, and for actuating said selector valve to determine the speed of such traverse.

19. In a machine of the class described, a work holder, a tool, power means for producing relative traverse between said holder and tool, means for controlling the speed of traverse between a relatively slow working speed and a relatively fast idle speed, and mechanism effective when said controlling means is in working speed condition and ineffective when said controlling means is in fast speed condition for producing a dwell in said traverse at an end thereof, said mechanism including means for cutting off power to stop said traverse.

20. In a machine of the class described, a work holder, a tool, means for producing relative traverse between said holder and tool, means for controlling the speed of traverse between a relatively slow working speed and a relatively fast idle speed, means effective when said controlling means is in working speed condition and ineffective when said controlling means is in fast idle speed condition for producing a dwell in said traverse at the ends thereof, and means for independently adjusting the duration of said dwells at opposite ends of said traverse.

21. In a machine of the class described, a work holder, a tool, hydraulic means for producing relative traverse between said holder and tool, a valve actuatable to select the rate and direction of such traverse and to check the speed of said traverse from the selected rate to a definite low speed adjacent to traversing limits, and means acting, when said valve is moved to effect change in direction of said traverse, to stop such traverse from such low speed and hold it stopped for a predetermined period and then to cause said hydraulic means to produce traverse in the reverse direction.

22. In a machine of the class described, a work holder, a tool, a hydraulic motor for effecting

- traverse between said tool and holder, a fluid-actuated valve for cutting off and reversing fluid connections to said motor to reverse the direction of traverse, a control valve for said reversing valve having means for selecting any of a plurality of speeds of traverse and for reducing the speed of traverse from any selected speed to a definite low value adjacent to traversing limits, and means for delaying the motion of said reversing valve so as to close said fluid connections to stop said traverse from said definite low speed and hold said connections closed for a predetermined period to effect a dwell in said traverse before reversing said connections to start said traverse in the reverse direction.
23. In a machine of the class described, a work holder, a tool, a hydraulic motor for effecting traverse between said tool and holder, a fluid-actuated valve for cutting off and reversing fluid connections to said motor to reverse the direction of traverse, a control valve for said reversing valve having means for selecting any of a plurality of speeds of traverse and for reducing the speed of traverse from any selected speed to a definite low value adjacent to traversing limits, and means for delaying the motion of said reversing valve in an intermediate portion only of its motion so as to close said fluid connections to stop said traverse from said definite low speed and hold said connections closed for a predetermined period to effect a dwell in said traverse before reversing said connections to start said traverse in the reverse direction, and to produce quick closing and opening of said connections.
24. In a machine of the class described, a work holder, a tool, a hydraulic motor for producing relative traverse between said holder and tool, a fluid-actuated valve for cutting off and reversing fluid connections to said motor, and a control valve for said reversing valve, said control valve having means for throttling the discharge from said motor to reduce the speed of traverse just before actuating said reversing valve to stop and then reverse the direction of said traverse.
25. In a machine of the class described, devices comprising a work holder and a tool, a bar, bearings supporting said bar for axial and rocking motion, an arm carried by said bar and supporting one of said devices for cooperation with the other, means for moving said bar axially, and means for forcing oil under pressure to said bearings and beneath said bar to thereby aid in supporting the weight of said bar and arm and the device carried by said arm.
26. In a machine of the class described, devices comprising a work holder and a tool, a bar, bearings supporting said bar for axial and rocking motion, an arm carried by said bar and supporting one of said devices for cooperation with the other, hydraulic means for moving said bar axially, and connections from said means for conducting fluid under pressure from said means to said bearings beneath said bar to aid in supporting the weight of said bar and said arm and the device carried by said arm.
27. In a machine of the class described, a work holder, a tool, a hydraulic motor for effecting traverse between said tool and work holder, and control means for said motor including a reversing valve determining by its position the speed of valve determining by its position the direction of traverse, a selector valve determining by its position the speed of traverse, and a pilot valve determining by its position the positions of said reversing and selector valves.
28. In a machine of the class described, a work holder, a tool, a hydraulic motor for effecting traverse between said tool and work holder, and control means for said motor including a reversing valve determining by its position the direction of traverse, a selector valve determining by its position the speed of traverse, and a pilot valve determining by its position the positions of said reversing and selector valves and effective before actuating said reversing valve to reverse the motor to slow the traversing speed of said motor.
29. In a machine of the class described, a work holder, a tool, a hydraulic motor for effecting traverse between said tool and work holder, and control means for said motor including a reversing valve determining by its position the direction of traverse, a selector valve determining by its position the speed of traverse, and a pilot valve determining by its position the positions of said reversing and selector valves and effective only when said selector valve is in feed speed position before actuating said reversing valve to reverse the motor to slow the traversing speed of said motor.
30. In a machine of the class described, a work holder, a tool, a hydraulic motor for effecting traverse between said tool and holder, a valve for said motor movable axially to control the direction of such traverse and rockable to determine the speed and limits of such traverse, and means acting in one angular position of said valve to slow the rate of traverse adjacent to the traverse limits then to stop said traverse from said slower speed and then after a dwell to reverse the direction of traverse.
31. In a machine of the class described, a work holder, a grinding wheel, a hydraulic motor for effecting traverse between said wheel and holder, a valve for said motor movable axially to control the direction of such traverse and rockable to determine the speed and limits of such traverse, a wheel dressing tool, and means actuatable at one portion of the traverse and only when said valve is in one angular position for bringing said tool into dressing relation to said wheel.
32. In a machine of the class described, a grinding wheel, a work holder, a hydraulic motor for effecting traverse between said wheel and work holder, a wheel truing device, a member movable in one path to determine the direction of traverse, a selector valve controlled by said member and determining from the position in another path of said member the speed of such traverse, and means controlled by said selector valve for moving said device into and out of operative relation to said wheel in one position of said member in said other path.
33. In a grinding machine having a work table and a rotating grinding wheel, wheel truing means, a variable speed driving motor to effect relative reciprocation between the table and the grinding wheel, means under the control of the operator for controlling the rate of reciprocation, means for slowing the motor to a predetermined slow rate prior to reversal, means under the control of the operator for starting and stopping the reciprocation, a wheel truing control for the machine comprising a selector device having alternative truing and inoperative positions, and connections rendered operative by the movement of said control to truing position to render said means for slowing the motor inoperative.

and to connect said motor for operation at a predetermined truing speed.

34. A machine of the class described, comprising a traversing carriage, devices comprising a work holder and a tool, one only of said devices being carried by said carriage, said machine including a source of hydraulic pressure, a reversible hydraulic motor, connections from said motor for moving said carriage, a reversing valve, fluid connections from said reversing valve to said motor causing the position of said valve to control the flow of fluid to drive said motor in opposite directions, means for varying the normal speed of said motor and thereby the normal speed of said carriage, flow throttling means, positive connections between said carriage and said throttling means to actuate said throttling means to slow the flow of fluid through said motor to a predetermined value less than said normal speed when said carriage reaches a predetermined point in its traverse, fluid pressure reversing-valve actuating means, and means actuating said hydraulic reversing-valve-actuating means after said carriage motion has been so slowed to move said reversing valve to stop and then reverse said motor from said predetermined low value.
35. A machine of the class described, comprising a traversing carriage, devices comprising a

work holder and a tool, one only of said devices being carried by said carriage, said machine including a source of hydraulic pressure, a reversible hydraulic motor, connections from said motor for moving said carriage, a reversing valve having reverse fluid connections and fluid flow checking means, fluid connections from said reversing valve to said motor causing the position of said valve to control the flow of fluid to drive said motor in opposite directions, means for varying the normal speed of said motor and thereby the normal speed of said carriage, flow-throttling means, positive connections between said carriage and said throttling means to actuate said throttling means to slow the flow of fluid through said motor to a predetermined value less than said normal speed when said carriage reaches a predetermined point in its traverse, fluid pressure reversing-valve-actuating means, and means actuating said hydraulic reversing-valve actuating means after said carriage motion has been so slowed to move said reversing valve to trap the motor fluid in said motor by said checking means for a predetermined time to cause a dwell at the end of the carriage traverse, and then to reverse said motor connections to reverse the direction of traverse.

MERTON H. ARMS.

Patent No. 2,176,985.

MERTON H. ARMS.

October 24, 1939.

It is hereby certified that error appears in the printed specification of the above numbered patent requiring correction as follows: Page 2, second column, line 24, for the word "pumping" read jumping; page 10, first column, lines 72 and 73, claim 27, strike out "the speed of ing valve determining by its position"; and that the said Letters Patent should be read with this correction therein that the same may conform to the record of the case in the Patent Office.

Signed and sealed this 5th day of December, A. D. 1939.

(Seal)

Henry Van Arsdale,
Acting Commissioner of Patents.

and to connect said motor for operation at a predetermined truing speed.

34. A machine of the class described, comprising a traversing carriage, devices comprising a work holder and a tool, one only of said devices being carried by said carriage, said machine including a source of hydraulic pressure, a reversible hydraulic motor, connections from said motor for moving said carriage, a reversing valve, fluid connections from said reversing valve to said motor causing the position of said valve to control the flow of fluid to drive said motor in opposite directions, means for varying the normal speed of said motor and thereby the normal speed of said carriage, flow throttling means, positive connections between said carriage and said throttling means to actuate said throttling means to slow the flow of fluid through said motor to a predetermined value less than said normal speed when said carriage reaches a predetermined point in its traverse, fluid pressure reversing-valve actuating means, and means actuating said hydraulic reversing-valve-actuating means after said carriage motion has been so slowed to move said reversing valve to stop and then reverse said motor from said predetermined low value.
35. A machine of the class described, comprising a traversing carriage, devices comprising a

work holder and a tool, one only of said devices being carried by said carriage, said machine including a source of hydraulic pressure, a reversible hydraulic motor, connections from said motor for moving said carriage, a reversing valve having reverse fluid connections and fluid flow checking means, fluid connections from said reversing valve to said motor causing the position of said valve to control the flow of fluid to drive said motor in opposite directions, means for varying the normal speed of said motor and thereby the normal speed of said carriage, flow-throttling means, positive connections between said carriage and said throttling means to actuate said throttling means to slow the flow of fluid through said motor to a predetermined value less than said normal speed when said carriage reaches a predetermined point in its traverse, fluid pressure reversing-valve-actuating means, and means actuating said hydraulic reversing-valve actuating means after said carriage motion has been so slowed to move said reversing valve to trap the motor fluid in said motor by said checking means for a predetermined time to cause a dwell at the end of the carriage traverse, and then to reverse said motor connections to reverse the direction of traverse.
